UNITED STATES PATENT OFFICE.

HENRY PERCIVAL DIXON, OF LOS ANGELES, CALIFORNIA.

DISAPPEARING TABLE AND IRONING-BOARD.

1,315,913.

Specification of Letters Patent.

Patented Sept. 9, 1919.

Application filed January 8, 1919. Serial No. 270,203.

To all whom it may concern:

Be it known that I, HENRY PERCIVAL DIXON, a citizen of the United States, residing at Los Angeles, in the county of Los Angeles and State of California, have invented new and useful Improvements in Disappearing Tables and Ironing-Boards, of which the following is a specification.

This invention relates to a combined table and ironing board, which folds and is adapted to be cased on a wall or to be installed in recesses formed in a wall.

It is an object of this invention to provide a table suitable for use as a kitchen table, serving table, breakfast table and the like, in combination with an ironing board, all arranged to fold into a recess and be housed therein when not in use.

It is another object of this invention to provide a combined ironing board and table, in which the use of either the board or table does not impair the use of the other.

In addition to the broader features of this invention, there are certain details of design, whereby a simple, compact, durable and convenient structure of the class described, easy to install, and easy to open and close, is obtained.

I accomplish these objects by means of the embodiment of my invention illustrated in the accompanying drawing, in which:

Figure 1 is a central section through the device in folded position and within its cabinet. Fig. 2 is a front plan view of the cabinet closed, the position of the table and ironing board being shown in dotted lines. Fig. 3 is a fragmentary section on an enlarged scale taken on the line 3—3 of Fig. 2. Fig. 4 is an enlarged fragmentary side view of the connections between the ironing board and table at the lower end when in folded position. Fig. 5 is a central section through the cabinet and table, when in open position, the ironing board having been removed and the leaves of the table unfolded. Fig. 6 is a section similar to Fig. 5 showing the ironing board in position for use. Fig. 7 is a perspective view of the cabinet, ironing board, and table, the latter being opened for use.

Referring more particularly to the drawing, 8 is a cabinet of such dimensions that it will readily fit into the wall between the studdings of any of the ordinary and usual

building structures. The cabinet is open at 55 the front and provided with an upper door 9 and a lower hinged panel 10.

The panel 10 is hinged to the cabinet at the lower end and provided with hinges 11 at its upper end. Secured to the leaves of 60 the hinges 11 is a table 12. The table 12 has leaves 13 upon either side thereof and is herein shown secured thereto by means of butt hinges. The leaves may be folded upon the top of the table, as indicated in Figs. 1, 65 2, 3, 4 and 6. It will be noted that the outer corners of the leaves 13 are rounded as indicated by 14 and for a purpose later described.

Secured to the inner end of the table is a 70 guide pin 15. Guide pin 15 is secured upon the upper surface of the table and rides in slots 16 formed in the inner side walls of the cabinet 8 terminating at their upper ends in notches 17. This forms a drop connection. 75 Fastened on the side walls of the cabinet at the lower end of notches 16 are blocks 18 for the table and board to rest thereon. It will be noted that there is a single slot upon each side of the cabinet.

An ironing board 19 has extending across its lower end a cleat 20 provided with forwardly extending dowel pins 21, which engage corresponding holes in the guide pin 15. The cleat 20 clears at its end the blocks 80 18, so that when the ironing board and table are in the folded position shown in Fig. 1, both the board and table will be supported upon the blocks. Upon the ironing board adjacent its upper end is a centering block 90 22, which extends from the surface of the table and nests in the space between the rounded corners 14 of the table leaves. This centering piece insures the proper position of the outer end of the board for registration of the end of an elbow catch 23 fastened to the block and its keeper 24 fastened to the table. It also holds the outer end of the board against sidewise movement with respect to the table.

Assume that the table and ironing board are in closed position within the cabinet, as shown in Figs. 1 and 2. To use the ironing board, door 9 is opened, and the ironing board grasped at the top and pulled outwardly. The ironing board is fastened to the table at the inner end by means of the dowel pins 21 engaged with the guide

pin 15 together with the elbow catch 23 which locks the front end of the ironing board to the table and the centering block 22 preventing sidewise movement. The 5 panel 10 swings outwardly and guide pin 15 rides in the slots 16 to their upper ends and then into the notches 17. The final position is that shown in Fig. 6. The table and ironing board are held in their open position by the support of the panel 10 and the notches 17.

If it is desired to use the table alone, the door 9 is opened and elbow catch 23 released from engagement with its keeper 24. This 15 will permit the table to be pulled forward away from the ironing board. The guide pin 15 as it rises in its slot 16 is released from the dowel pins 21 on the ironing board cleat, thereby completely freeing the table 20 from the ironing board. The latter remains in the cabinet resting upon blocks 18. When the table 12 has reached its open position, the leaves 13 are unfolded, and the table appears as shown in Figs. 5 and 7. The 25 leaves in open position overlap the sides of the cabinet and prevent the table from collapsing by accidental pressure toward the rear.

If it is desired to remove the ironing 30 board and use it in another place, the board is opened as shown in Fig. 6. The catch is released and the end of the board lifted. The board is then pushed backward toward the back wall of the cabinet, thereby releasing the dowel pins 21 from engagement 35 with guide pin 15. The board is thus entirely released and may be carried about and placed in any position desired. To replace the board, the reverse operation to that just 40 described is effected.

The operation of closing the table and board is obvious. The table with or without the board is swung upward the rear of the table dropping in the cabinet. The panel 45 10 is then pushed inward, thereby completely folding the table and board in the cabinet. The door 9 is then closed so that

the table and board have completely disappeared in the wall.

What I claim is:

1. A combined ironing board and table, comprising a cabinet; a table having its rear end secured to said cabinet so as to drop therein, said table having leaves with rounded corners foldable onto the top 55 thereof; an ironing board unattached to said cabinet having a centering piece for nesting in the space formed by the rounded corners of the leaves when folded; means detachably securing the rear of the ironing 60 board to said table; and means detachably securing the front of said board to said table.

2. A combined ironing board and table, comprising a cabinet having slots formed 65 in the sides thereof; a table having a guide pin riding in said slots; leaves foldable onto the top of said table; an ironing board unattached to said cabinet having means thereon for detachably engaging the front 70 of the table; and a cleat on said ironing board overhanging the rear of said table and provided with dowel pins engageable with bores in said guide pin.

3. A combined ironing board and table, comprising a cabinet having slots formed in the sides thereof; a table having a guide pin riding in said slots, said table having leaves with rounded corners foldable onto the top thereof; a lower panel hinged on said cabinet and pivotally connected to said table; an ironing board unattached to said cabinet having a centering piece for nesting in the space formed by the leaves when folded, a cleat on said ironing board overhanging 80 said table and having dowel pins engageable with bores in said guide pin; and a catch to detachably secure the front of said board to said block.

In witness that I claim the foregoing I 90 have hereunto subscribed my name this 2nd day of January, 1919.

HENRY PERCIVAL DIXON.
